BARBECUE GRILL

A. Baker Barnhart, New York, N. Y., assignor to Mortimer R. Meyer, Flushing, N. Y.

Application February 23, 1950, Serial No. 8,080

Term of patent 3½ years

(Cl. D81—10)

To all whom it may concern:

Be it known that I, A. Baker Barnhart, a citizen of the United States of America, and a resident of New York, in the county and State of New York, have invented a new, original, and ornamental design for a Barbecue Grill, of which the following is a specification, reference being had to the accompanying drawing, forming part thereof, in which—

Fig. 1 is a perspective view of a grill embodying my new design, the opposite end of the grill being the same as the end shown.

Fig. 2 is a sectional view taken through the line 2—2 of Fig. 1.

I claim:

The ornamental design for a barbecue grill, as shown and described.

A. BAKER BARNHART.
